UNITED STATES PATENT OFFICE.

ABEL B. WOODWARD, OF NASHVILLE, TENNESSEE.

BRICK-MACHINE.

SPECIFICATION forming part of Letters Patent No. 330,953, dated November 24, 1885.

Application filed September 29, 1885. Serial No. 178,555. (No model.)

To all whom it may concern:

Be it known that I, ABEL B. WOODWARD, a citizen of the United States, residing at Nashville, in the county of Davidson and State of Tennessee, have invented a new and useful Improvement in Brick-Machines, of which the following is a specification, reference being had to the accompanying drawings.

My invention has relation to improvements in brick-making machinery; and the novelty consists in the peculiar construction, arrangement, combination, and adaptation of the various parts for service, substantially as hereininafter fully described, and specifically pointed out in the claims.

In the accompanying drawings, which form a part of this specification, Figure 1 is a side elevation of my improved brick-machine. Fig. 2 is an end elevation. Fig. 3 is a vertical transverse section through one set of the plungers and their operating mechanisms on the line $x-x$ of Fig. 1. Fig. 4 is a vertical longitudinal section on the line $y-y$ of Fig. 3. Fig. 5 is a detail view of the mechanism for automatically returning the upper compression-plunger to its normal position to be acted upon by the cams. Fig. 6 is a detail view of the hopper and its actuating mechanism. Fig. 7 is a detail view of the gage. Fig. 8 is a side view of the lower cam, and Fig. 9 is a view showing my preferred form of driving or sprocket chain.

Like letters of reference in the several figures of the accompanying drawings denote corresponding parts.

The invention is especially designed as an improvement in that class of brick-making machinery known to the art as "reciprocating brick-machines;" and it has for its objects, among other things, to provide for the bottom or lower platen of the molds or dies by so arranging and timing the movements of the lower or expelling plunger that its die shall form the bottom to said molds while the material is being fed thereto and the upper compression-plunger is acting on the material in said molds, after which the expelling-plunger forces the compressed and formed brick out of the molds.

A further object of my invention is to provide improved means for automatically operating the reciprocating hopper; to provide

scrapers for cleaning the faces of the plungers from any material that may adhere thereto; to provide means for automatically returning the compression-plungers from the molds when released by the depressing-cams, and to combine simplicity with great strength and durability in the construction, and which shall be thoroughly effective and automatic in operation and without any undue strain or wear upon the several parts of the machine.

Referring by letter to the drawings, A designates the frame of the machine, which comprises four upright posts or pillars, A', secured or bolted at their lower ends upon beams A'', and connected at their upper and lower ends by horizontal beams or bars A''', and intermediately between such upper and lower beams by horizontal beams A'''. Bolts are passed through the posts or pillars, and have their ends threaded to receive nuts a , to tighten the tension under which the frame is held together.

B designates the molds, arranged in the plane of and secured in any suitable manner to the beams A''', and arranged in series in a horizontal plane. The molds B are provided with guides b , which depend from their lower surfaces at the side edges and ends thereof, and between these guides moves the frame of the expelling-plunger C, arranged below the molds and adapted to be forced upwardly therein.

D designates the upper compression-plunger, arranged above the plane of the molds and adapted to be forced downwardly therein.

E designates a shaft journaled in proper journal boxes or bearings, e , secured to the lower horizontal beams of the machine-frame. This shaft E carries two cam-wheels, E', near its middle, beneath the reciprocating expelling-plunger, and at its ends it projects beyond the frame A and carries a sprocket-wheel, E'', at each end, one of the sprocket-wheels having a crank-pin, e' , for the attachment of a driving-piston from a steam-engine or other motor, thus making the shaft E the driving-shaft.

F designates a shaft arranged in the plane of the shaft E and journaled or mounted in boxes f , secured to upper horizontal beams of the main frame, said shaft being provided with cams F', arranged at different angles to their

shaft than the cams of the shaft E, and to work or operate on their plungers at a different time. This shaft F is extended beyond its bearings in the main frame, and carries a 5 sprocket-wheel, F², at each end, similar in construction and size to the sprocket-wheels of the shaft E, with which they are geared or connected by a sprocket-chain, G, the preferred form of which I illustrate in detail in 10 Fig. 9. The lower expelling-plunger, C, comprises a bar, c, having a series of platens, c', on its upper surface, and on its lower surface it is provided with depending arms c'', which are arranged between the guides b of the molds 15 and are free to slide or reciprocate up and down therein.

c³ c⁴ designate friction or bearing rolls loosely or rotatively mounted in the lower ends of arms c² of the expelling-plunger, and normally kept in contact with the cams E', the frame of the expelling-plunger being drawn downwardly by gravity until its bearing frictional rolls c³ come in contact with the cams E', by which said plunger is held in position 25 and reciprocated to perform its office or duty in expelling or forcing the compressed brick from the molds B.

The upper compression-plunger, D, is arranged between guides or ways D', secured to 30 the upper horizontal beams, A³ A⁴, above the plane of the molds B, to leave an intermediate space for the passage of a reciprocating hopper, I, said guides D' receiving the frame of the compression-plunger. This plunger is 35 similar in its construction to the expelling-plunger. It has a bar or platen, d, having projecting dies d' on its lower surface and guide-arms d'' arranged between the guides D', the upper ends of said arms d'' being bifurcated to embrace the shaft F, with which they 40 are arranged in close juxtaposition.

d³ designates friction or bearing rolls pivoted or hung loosely in the guide-arms d'', above the bar d thereof, and adapted to be operated 45 upon by the cams F' to force the dies of the platen into the molds to compress the material fed thereto by the hopper.

The guides D' are provided with protecting and guiding strips or walls at their sides, as 50 shown, and the shafts of the rollers d³ are projected through vertical slots f', formed or cut in the end guides, D', and receive a friction-roller, f'', the office and function of which will appear more fully hereinafter.

55 The vibrating or reciprocating hopper I comprises two casings and chambers at right angles to each other, to receive the clay or other material from a conducting-spout, said hopper I having supporting-bars i at its ends, 60 arranged to bear on the upper surface of the mold at the side edges thereof, and work in guides I', secured to the molds, as shown.

J designates a rock-shaft journaled in bearings j, secured to the frame A, and having 65 arms J' at each end projecting inwardly, and arranged in the plane of rotation to be struck or operated by curved operating-plates K, se-

cured to each of the sprocket-wheels of the shaft E. The arms J' are arranged at different angles to their supporting-shaft J, and are 70 each provided with a loosely-mounted friction-wheel, j', adapted to be successively struck or operated by the arms of the sprocket-wheels for the purpose of forcing and retracting the hopper I forward and backward from the 75 molds.

The rock-shaft J is connected with the hopper I by means of upright bars or standards L, arranged at each side of the main frame, and having an opening in its upper end, and through this opening of each of the 80 bars L passes the outer threaded end of an arm, L', which receives the two nuts e'', arranged to bear on opposite sides of the slotted end of the bar L, to adjustably connect the said bar to the hopper I to vary or regulate 85 the length of movement or stroke of the hopper, the inner ends of the arm L' being pivotally connected at each side of the hopper thereto. The arms or plates K are arranged at a varying angle to the sprocket-wheels on 90 which they are mounted, so as to be successively brought to strike against and oscillate the arms of the rock-shaft, one of said plates striking against one of the arms to force the hopper inwardly to the molds, and just sufficient time is allowed to permit of such inward movement and discharge of the clay or other material into the molds before the opposite arm or plate K strikes the opposite arm 95 of the rock-shaft to draw the hopper rearwardly away from the molds, this operation being continued as long as the machine is in motion. The sprocket-wheels F² of the upper cam-shaft, F, are provided with lifting arms or brackets M, each sprocket-wheel having one of 100 said brackets arranged on its inner surface at the periphery thereof. The main portion of said arms or brackets M is arranged in the arc of a circle concentric with the outer periphery of the sprocket-wheels, while their forward ends 105 are tapered, as at m, and their rear ends beveled or rounded off, as at m', to permit the device to readily take under and leave the friction-rollers f' of the upper compression-plunger, 110 to elevate said plunger and withdraw its dies from engagement with the molds, to permit the compressed brick to be discharged or expelled from said molds by the upward movement of the lower expelling-plunger, such upward movement taking place simultaneously with the withdrawal of the compression-plunger from the molds.

In lieu of thus positively operating or elevating the the upper compression-plunger by the action of the lifting-brackets M, a mechanism may be 115 employed to keep the said plunger normally elevated out of engagement with the molds and in contact with the cams F', operating to depress or force the compression-plunger into the molds, such automatic elevating device 120 permitting of the depression of such plunger.

N designates two plates arranged in a vertical position alongside of the main frame, above the roller-shaft of the rollers f', the

lower ends of said plates being bifurcated, to embrace the journal-pin of said rollers f' and be connected thereto. The upper ends of the plates N , which are adapted to move vertically with the upper compression-plunger, are pivotally connected to the bent ends of the arms of a vertically-sliding bail, N' , which projects above the plane of the upper periphery of the sprocket-wheels F^2 . The arms of this bail N' are arranged to pass through slots or recessed portions of the upper horizontal beam, A^3 , of the frame, and be thus guided in its vertical movements, and said bail carries a rigid arm, n , arranged in a horizontal position at right angles to the bail, this arm being fulcrumed at or near its middle on a supporting bracket or arm, O' , secured to and projecting from the main frame, said arm or beam n having a weight, O , at its outer extremity. It will thus be seen that the weighted arm n will keep the vertically-sliding plate and bail normally pressed upward, and consequently the compression-plunger, and keep the friction-rollers thereof in engagement with the cams F' , and the dies of the platen thereof elevated out of the forming-molds. I have found by experiment that this plunger actuating or lifting device, which comprises the plate, bail, and weighted arm, will give good and beneficial results; but to insure harmony and ease of action without subjecting the parts thereof to any undue strain or wear, I have deemed it best, although not essential, to employ the lifting brackets or arms M , arranged on the sprocket-wheels F^2 , and adapted to operate, in connection with such automatic lifting device, to lift the compression-plunger when the cams F' have ceased to act on the friction-rollers thereof.

The operation of my invention is as follows: Clay or other material is fed to the reciprocating hopper, and the machine is started by applying power to one of the sprocket-wheels of the shaft E . The rotation of said sprocket-wheels causes one of the curved arms or plates K thereof to strike one of the arms J' of the rock-shaft J , which is thus oscillated, and communicates its motion to the reciprocating hopper I to force it forward. Simultaneously with the forward movement of the hopper the lower expelling-plunger is forced upwardly by the cams E' into the molds to form bottoms or platens thereto, and the upper compression-plunger is also simultaneously withdrawn from said rolls by the joint action of the weighted lever and the lifting-brackets, or by either one of them independently of each other, the projecting rib or cam surface on the cams F' being withdrawn, or turned so as to be out of engagement with friction-rollers of said compression-plunger. The other curved arm or plate K now comes in contact with the other arm of the rock-shaft, causing it to turn or oscillate in its bearings in the opposite or reverse direction to its first movement, and withdrawing the hopper from the molds to receive a new charge of clay or other material. The

cams F' are now brought to act or bear on the compression-plunger and force the same down into the molds onto the surface of the material therein to compress the same firmly and compactly, the lower expelling-plunger remaining stationary during these two latter movements. The compression-plunger is now withdrawn from the molds, and simultaneously with such withdrawal thereof the lower expelling-plunger is moved upwardly into the molds by the revolution of the cams E' to force the compressed and formed brick from the molds, and when the bricks have been completely elevated out of the molds they are forced onto a carrying or discharging device (not shown) by the forward movement of the reciprocating hopper, which has been again actuated by the plates K and rock-shaft J . When the hopper is at its forward stroke, the lower compression-plunger drops to its normal position to form the bottom to the molds, said frame dropping by gravity when the cams have been revolved; and these successive steps in the operation of the machine are continued in order to compress the brick, the whole operation being performed automatically and without requiring the presence of an attendant.

Any preferred form of conveying apparatus may be employed to carry the formed pressed bricks away from the machine; but as such a device does not constitute part of the present invention, I have not deemed it necessary to illustrate the same. An idle wheel or pulley, P , mounted on a pin or shaft, p , supported in the main frame, is employed to bear against the endless traveling belt G , connecting the sprocket-wheels E^2 F^2 , to keep the belt taut and under proper tension, one pulley P being employed to each belt. The pulley or wheel may be made adjustable to vary the tension of said belt.

The upper and lower edges of the front end of the vibrating or reciprocating hopper I are provided with scraping-blades Q , arranged to clean or clear the lower and upper faces of the compression and expelling plungers of any clay or other material that may adhere thereto, such clearing operation being performed by the blades when the lower plunger forces or expels the brick from the molds, and the upper plunger is withdrawn therefrom.

I do not desire to limit myself to the particular construction shown and described, as I am aware that many changes may be made therein and in the form and proportions of the various parts without departing from the principle or sacrificing the advantages of my invention, the essential features of which have been explained and will be readily understood from the foregoing description, taken in connection with the drawings.

A casing or shield, R , is secured to the guides b of the molds to protect and guide the friction-rollers of the gravitating expelling-plunger.

In Fig. 7 I show a gage for regulating the

depth which the platens of the lower expelling-plunger lie in the mold. The lower faces of the arms c^2 of said lower expelling-plunger are beveled and engage the beveled face of a 5 supporting gage-block, S, rigidly secured to the squared portion of a shaft, S', bearing at its ends in supports s' , secured to the main frame, and having one of its ends threaded and provided with an adjusting-nut, S². The shaft is 10 free to turn in its bearings, and can be adjusted back and forth therein to bring the beveled face of the gage-block nearer to or farther from the center of the lower beveled supporting-arms, c^2 , of the gravitating expelling- 15 plunger.

In Fig. 8 of the drawings I have shown in detail one of the cams on the lower shaft for actuating the lower gravitating expelling-plunger. The outer periphery of each of the lower 20 cams has three bearing points or surfaces, $t t' t^2$, at different distances from the center and concentric therewith. The first of the bearing-surfaces, t , is in engagement with the friction-roller of the expelling-plunger after it has 25 turned to its normal position after expelling or forcing the brick from the molds, and said cam-surface serves to hold the platens of said plunger in the bottom of the molds to form the bottoms thereto when the earth or 30 clay has been deposited in the molds by the hopper. The second bearing-surface, t' , is at a little greater distance from the center of the cam and projects beyond the periphery of the 35 surface t , and serves to advance the lower plunger in the molds for a short distance, and operates to elevate said lower plunger simultaneously with downward stroke of the upper 40 compression-plunger, and thus serves to compress the clay or earth in a slight degree by shortening the distance between the two plungers, which is important when dry earth is 45 fed to the molds, and the third extended bearing-surface, t^2 , lies at a greater distance beyond the center of the cam than either of the 50 surfaces t or t' , and at a distance from the latter surface, t^2 , equal to the distance which the platens of the expelling-plunger lie from the tops of the molds when the material is being 55 compressed therein, and said cam-surface t^2 acts to force the lower expelling-plunger upward to force out the brick from the molds simultaneously with the withdrawal of the compression-plunger therefrom, all as will be very readily understood.

Having thus fully described my invention, what I claim as new, and desire to secure by Letters Patent, is—

1. In a brick-machine, the combination, with the molds, of a lower expelling-plunger, a 60 compression-plunger, and an automatic lifting device connected with said compression-plunger for holding the same normally from engagement with the molds, substantially as described.

2. In a brick-machine, the combination of the molds, a compression-plunger, a shaft having cams for depressing said plunger, and

lifting devices mounted on the cam-shaft and separate from the compression-plunger, to elevate said plunger out of the molds at the proper interval, substantially as described. 70

3. In a brick-making machine, the combination, with the molds, of a gravitating expelling-plunger, a compression-plunger normally held from engagement with the molds, two shafts 75 having cams mounted in the machine-frame beneath and above the expelling and compression plungers, and an automatic lifting device connected with and separate from said compression-plunger, to keep the same normally in engagement with its actuating cam-shaft, substantially as described. 80

4. In a brick-making machine, the combination, with the molds, of a gravitating expelling-plunger, an upper compression-plunger, cam-shafts arranged beneath and above the expelling and compression plungers and geared together, lifting arms or brackets mounted on the cam-shaft of the compression-plunger, and a weighted arm and intermediate connections 90 pivotally secured to the shaft of the compression-plunger at each end thereof, substantially as described. 95

5. In a brick-machine, the combination of the molds having depending guides, a gravitating expelling-plunger working in said guides and having frictional rolls, guides for the upper compression-plunger, a compression-plunger carrying frictional rolls at its middle, and having friction-rolls arranged thereon exterior to the guides of said plunger, cam-shafts for said plungers, geared together, and lifting device for said compression-plunger, arranged to act on the outer friction-rolls thereof, substantially as described. 105

6. In a brick-making machine, the combination of a frame, molds mounted therein, the compression and expelling plungers, cam-shafts for actuating said plungers and carrying sprocket-wheels, an endless traveling belt connecting said cam-shaft sprocket-wheels, a reciprocating hopper arranged to move between the plungers, a rock-shaft mounted in the frame and having arms connected with the hopper, and operating-plates secured to the sprocket-wheels of the lower cam-shaft and arranged to successively operate the rock-shaft to oscillate the same and the hopper, substantially as described. 110

7. In a brick-making machine, the combination of a frame, molds mounted therein, a compression and expelling plunger, shafts having cams mounted in the frame for operating the plungers, and carrying sprocket-wheels geared together, a reciprocating hopper having guides working between the plungers and carrying scraping-blades, a rock-shaft mounted in the frame and having arms carrying frictional rolls, operating-plates mounted on the sprocket-wheels of the lower cam-shaft and arranged to successively strike the frictional rolls of the rock-shaft arms, upright bars secured to the rock-shaft and having slotted ends, and arms pivotally connected to the 120 125 130

hopper and having threaded ends carrying nuts, substantially as described.

8. The combination, with the compression-plunger having its frictional roller-shaft extended, and the slotted guides therefor, of a vertically-sliding plate connected to said shaft at each end thereof, a bail pivotally connected to each plate, a bracket secured to the frame of the machine at the sides thereof, and a weighted arm mounted in each of said brackets and connected to the bail-arm, substantially as described.

9. In a brick-machine, the combination of a frame, a mold or molds mounted therein, a gravitating expelling-plunger arranged to form a bottom to said mold or molds, a compression-plunger, lifting devices therefor separate from the compressing devices, a reciprocating hopper arranged to move between the plungers and over the mold or molds, and means, substantially as described, whereby the compression-plunger is withdrawn from the molds simultaneously with the upward movement of the expelling-plunger and the forward movement of the reciprocating hopper, substantially as described.

10. In a brick-machine, the combination, with the molds and the compressing and expelling devices, of a reciprocating bottomless

hopper having closed ends and sides to provide a preliminary forming-chamber, and having a receiving-throat communicating therewith and arranged at an angle thereto to conduct the earth into said hopper, substantially as described.

11. In a brick-machine, and in combination with the molds and the expelling and compression plungers, a shaft having cams for actuating said plungers, each cam of the expelling-plunger shaft having three raised portions that lie at different distances from the center thereof, and are successively brought to act upon the expelling-plunger to maintain the same normally within the molds, to form a bottom thereto, to slightly elevate the said plungers simultaneously with the downward stroke of the compression-plunger into the molds, and to force or expel the brick from the molds simultaneously with the withdrawal of the compression-plunger therefrom, substantially as described.

In testimony that I claim the foregoing as my own I have hereto affixed my signature in presence of two witnesses.

ABEL B. WOODWARD.
